FLAIL FOR MATERIAL SPREADERS

Jacob Henry Lepp, 16 Cherry Drive, Grimsby, Ontario, Canada, and Edward Kuta, 117 Wise Crescent, Hamilton, Ontario, Canada

Filed Sept. 28, 1964, Ser. No. 81,899

Term of patent 14 years

(Cl. D35—2)

FIG. 1 is a front perspective view of a flail for material spreaders embodying our new design;

FIG. 2 is a side view as seen from the right of FIG. 1;

FIG. 3 is a front view of the flail;

FIG. 4 is a side view as seen from the left of FIG. 1;

FIG. 5 is a rear view of the flail;

FIG. 6 is a top view of the flail;

FIG. 7 is a bottom view of the flail;

FIG. 8 is a section taken on line 8—8 of FIG. 2; and

FIG. 9 is a section taken on line 9—9 of FIG. 2.

We claim:

The ornamental design for a flail for material spreaders, as shown.
